PHOTO ENLARGING APPARATUS

Carlos Cortez Valle, Las Vegas, Nev., assignor to Photo
Button Industries, Inc., Las Vegas, Nev.

Filed Aug. 23, 1974, Ser. No. 500,160

Term of patent 14 years

Int. Cl. D16—03

U.S. Cl. D61—1 Q

FIGURE 1.

FIGURE 2.

FIGURE 3.

FIGURE 4.

FIGURE 5.

FIGURE 6.

FIG. 1 is a perspective view of the photo enlarging apparatus showing my new design;
FIG. 2 is a front elevational view thereof;

FIG. 3 is a top plan view thereof;

FIG. 4 is a rear elevational view thereof;

FIG. 5 is a left side elevational view thereof; and

FIG. 6 is a right side elevational view thereof.

I claim:

The ornamental design for a photo enlarging apparatus, as shown and described.
